AIR CONDITIONING SYSTEM

Walter L. Fleisher, New City, N. Y.

Application October 31, 1934, Serial No. 750,769

7 Claims. (Cl. 261—115)

This invention relates to air conditioning systems, and more particularly to methods of and means for producing and maintaining desired atmospheric conditions in enclosures.

5 The principal object of the invention is to provide a system for conditioning air, in which all air handled by the system is treated for purposes of temperature and humidity regulation, and which assures delivery to the enclosure 10 of air at a predetermined temperature and relative humidity.

In accepted air conditioning practice, it is usual to condition a volume of air by passing the air through a cold water spray or over surface coolers 15 through which a suitable refrigerating medium is circulated. The treated air is thereby reduced to a temperature below its dewpoint, and its excess absolute humidity precipitated. This air will then be too cold for comfort, and also, at a 20 relative humidity of about one hundred per cent, i. e., substantially saturated. Since this air cannot safely be introduced directly into the room or enclosure constituting the conditioned area, it must be reheated. The reheating is ordinarily 25 accomplished in accordance with present accepted practice, by adding to the conditioned air a volume of air from the enclosure under proper regulation. As a result, a tempered mixture is formed at a comfortable temperature, 30 higher than that of the conditioned air and at a proper relative humidity, lower than that of the conditioned air.

A feature of the invention resides in the conditioning of all instead of part of the air handled 35 by an air conditioning system, wherein all the air passes through one or more series of sprays, and yet, the final condition of the air is comfortable. In achieving this result, applicant arranges his sprays so that different sprays will 40 serve predetermined portions of the cross-sectional area of the conditioning apparatus. Thus, one series of sprays may be arranged to extend fully across the apparatus; another, to serve a cross-sectional area only two-thirds across; a 45 third, only half across; and so on.

Another feature of the invention, therefore, resides in the provision of sprays preferably made up of finely divided particles of fluid refrigerating medium so arranged that different sprays 50 will to varying degrees condition different portions of a total volume of air handled by a unitary air conditioning apparatus. Also, by providing a combination of sprays covering different cross-sectional areas of the same apparatus 55 through which all the air flows, a varying re-

sistance to the flow of air is provided at different points in the apparatus. Thus, the air stream is automatically proportioned so that different percentages thereof contact with the various sprays and this makes for a simple method of conditioning prescribed portions of a single air stream to different degrees.

A further feature covers the regulation either of a cooling medium under summer conditions, or a heating medium under winter conditions 10 fed to a series of sprays serving to cool and dehumidify or heat and humidify an air stream passing through the apparatus, responsive to load conditions affecting the conditioned area served by the apparatus.

Another feature provides for washing all of the air handled in a conditioning system, even though all of the air is not reduced below its dewpoint under summer operating conditions. Thus, precipitation of dirt and dust is assured, 20 even though the final temperature of the air is at a relatively comfortable level.

Further advantages covering simplicity in construction, ease and economy of operation, and effectiveness of control, will be more apparent 25 from the following description of a typical form of carrying out the invention, to be read in connection with the accompanying illustrative drawings, in which:

Fig. 1 illustrates diagrammatically an air conditioning system in which a series of diagonal sprays are employed in a washer through which all air handled by the system is passed.

Fig. 2 illustrates diagrammatically in fragmentary form, a modification of the spray arrangement utilized in Fig. 1; and

Fig. 3 is another modification in which the method of control embraces desired regulation of spray temperatures in different spray chambers or stages.

Fig. 4 is an elevational view of the embodiment of Fig. 3.

Considering the drawings, numeral 4 designates an enclosure such as a theatre, store, railroad car, or home, served by an air conditioning system shown to the left of the enclosure. The apparatus includes a conditioner 5 having an outdoor air intake 6 and return air intake 7, dampers 8 and 9 being regulated either manually or automatically to control the volumes of air entering conditioner 5 through said passages. Fan 10 delivers the conditioned air to the enclosure and returns air from the enclosure to the conditioner through return passage or passages 11. A suitable relief or exhaust may be provided to permit 55

an amount of air to escape from the enclosure equivalent to that admitted through dampers 8. In the conditioner 5, a series of spray headers 12, 13, 14 and 15 are provided to which conditioning medium from any desired source is suitably fed through inlet conduit 16 and common feed line 17. Under summer operating conditions, the medium will usually be refrigerated water supplied by a refrigerating system of required capacity and character. Under winter operating conditions, water of suitable temperature will be admitted upon the opening of valve 18 to header 19, so that the sprays 20 may be utilized for humidification purposes. Eliminators 21 remove entrained moisture from air discharged to the fan, and reheater 22 to which steam or other reheating medium is supplied under the control of valve 23, is utilized under winter operating conditions, in the usual manner.

Considering the operation of the system of Fig. 1 under summer operating conditions, thermostat or other suitable control instrument 24 responds to changes in atmospheric conditions in enclosure 4, and causes valves 12a, 13a, 14a and 15a to operate to admit refrigerant from conduit 17 to the corresponding spray headers 12, 13, 14 and 15. The valves are designed to open under different pressures. Thus, 12a may be designed to open under a pressure of 3 to 7 pounds. 13a will open under a pressure of 7 to 10 pounds. 14a will be operative under a pressure of 10 to 13 pounds, and 15a, under a pressure of 13 to 16 pounds. Assuming that conditions in the enclosure require a greater degree of cooling and dehumidification, the valve 12a will first open, thus admitting cold water to the sprays served by header 12. As may be noted in Fig. 1, header 12 is positioned diagonally across the washer; and while one header is shown, it should be understood that a series of interconnecting headers 12 may be provided, so that the washer from top to bottom will be served by sprays similar to the single row of sprays shown in Fig. 1. Of course, for small enclosures, it may only be necessary to use a single header with a single row of sprays, as shown in Fig. 1. As the depth of the casing 5 increases, a plurality of headers 12 in parallel, one above the other, would be provided. However, whether one header 12, or a plurality of headers 12 in parallel, one above the other, are used, is of no consequence, since the principle employed is the same. The result is that all air passing through the washer will be treated by the sprays from header 12. As the load in enclosure 4 increases, thermostat 24 will cause a greater air pressure to flow through line 25, so that valve 13a will then open, admitting refrigerating fluid to header 13. This will continue until sprays 14 and 15 also become operative, if required. The washer is designed to take care of peak load conditions, and under less than peak load conditions, it will not be required to utilize all the sprays. However, if any conditioning is required at all, the sprays from header 12 will first be utilized, thereby assuring treatment of all air passing through the washer.

It will be noted that when sprays additional to those of header 12 are used, they cover a cross-sectional area of the washer less than that covered by 12. As a result, some of the air will only pass through 12, whereas another portion will pass through the sprays from 13; a still-smaller portion will pass through the sprays from 14; and a relatively minor portion will pass through the sprays from 15. Consequently, the air which

passes through the sprays from header 12 will not be as intensively conditioned as that portion of the air which passes through the sprays from headers 12 and 13; and similarly, the air passing through three series of sprays will not be as intensively conditioned as that portion which passes through all of the sprays.

While the control will assure making operative additional series of sprays covering varying cross-sectional areas of the washer as conditions in the enclosure vary, the sprays themselves also have a regulating effect upon the conditioning of the air fed to the enclosure. For example, when header 12 alone is operative, all the air will pass through the sprays, but not all of the air will be reduced below the dewpoint. The medium fed to the sprays, such as cold water, will be at a desired dewpoint, but the volume of spray water compared to the fan capacity is so arranged that under the condition when spray header 12 alone is operative only a desired percentage of the total volume handled by the fan will be dehumidified. The remainder of the air will not be reduced below the dewpoint, and hence, will serve to form a mixture with the dehumidified portion higher in temperature than the dehumidified portion, and lower in relative humidity. Similarly, as additional sprays are cut in responsive to a rising load, the degree of conditioning of different portions of the single air stream will become greater, but the remaining portions will not be so intensively conditioned, and hence, the final temperature of the air entering the fan will be above the temperature of that portion which has been dehumidified below the dewpoint. Also, due to the diagonal arrangement, the resistance to the passage of air becomes progressively greater from the bottom to the top, or from side to side, of the casing as shown in Fig. 1, so that that portion of the air which is not so intensively conditioned does not as intimately contact with the sprays, and hence, is not conditioned to the same degree as that portion which, by reason of greater resistance, will not flow so rapidly through the sprays, and due to the difference in resistance, more air will pass through the less conditioned section to regulate the final condition of the air leaving the fan. This provides a greater percentage of "reheating air" in the final mixture which is what is required under normal operating conditions.

In Fig. 2, a modified form is shown wherein headers 26, 27 and 28 fed by a single source of conditioning medium through conduit 29, are arranged in V-form. While the V-form is used, it is apparent that semi-circular, or other forms of headers may be employed to achieve the same result. Thus, the air passing along the sides of the washer in the bands marked 30 will not be as intensively conditioned as those portions passing through the bands 31, which, in turn, will not be as intensively conditioned as the air passing through the middle of the V-formation. Similarly, the resistance to the air streams in bands 30 is least, and progressively grows greater towards the center of the conditioner. In operation, header 26 will first be cut in, whenever conditioning is required. All air going through the washer will thereby contact with the sprays, although, as pointed out in connection with Fig. 1, not all of it will be dehumidified to the same extent. Similarly, as in Fig. 1, headers 27 and 28 will become operative as the load in the enclosure increases, thus calling for a cooler condition of the air fed to the enclosure. The control in Fig. 2

could follow that of Fig. 1, although no limitation is made as to specific form of control. Any arrangement which will cause headers 27 and 28 to receive refrigerant as the load conditions in the enclosure increase, and to be cut out of service inversely as the load conditions decrease, is within the purview of the invention.

In Fig. 3, the washer is provided with stages 34, 35, 36 and 37. Valves 38, 39, 40 and 41 will respectively cause pumps 38a, 39a, 40a and 41a to operate to pump water to sprays 38b, 39b, 40b and 41b respectively. As in the case of Fig. 1, valve 38, under the control of thermostat 24, will operate under a pressure of 3-7 pounds, and the other valves will operate at progressively higher pressures. Cold water or the like, from the refrigerating source, will first feed into stage 34 through inlet 42 until it reaches a desired level under the control of a suitable liquid level device. It may then flow into stages 35, then to 36, and finally to 37, and then back to the refrigerating source through overflow outlet 43. The sumps of stages 35, 36 and 37 are at progressively lower levels, so that the liquid may flow by gravity through overflows from one stage to the other. Assuming that the load increases in the enclosure, thereby requiring conditioning of air, valve 38 would first open, causing water to be drawn from the sump of stage 36 and delivered to sprays 38b. As the load further increases, sprays 39b would be cut in, and similarly, sprays 40b and 41b. When all sprays are cut in, the sprays 41b would receive the coldest water, the sprays 40b water not so cold, and so on, the sprays 38b receiving the warmest water. Thus, in this arrangement, the warmest air will first meet the warmest sprays, whereas that portion of the air which is further conditioned will meet cooler sprays, and so on through the stages. Consequently, the air least conditioned, i. e., that air which passes through sprays 38b only, will serve as a reheating medium for the more intensively conditioned portion of the air which passes through the other stages too. The partitions 44 extend from the bottom of the washer to form confining walls for sumps in the different stages. The eliminators 45 and sprays rise above the level of partitions 44 to the top of the washer. The eliminators 45 are provided in each stage, so that the resistance to the flow of the air is increased in direct proportion to the degree it is conditioned. While partitions 44 between adjacent stages enables an overflow from one stage to the other, no overflow takes place from the last stage except through conduit 43 which provides an opening below the top of adjacent partition 44 of stage 37.

For resistance control through the washer, it may be desirable to provide a series of dampers such as 46, shown in Fig. 3. These may be controlled manually or automatically, so that one or more of the dampers may be opened, partially opened, or closed, to control the resistance to flow of air through different portions of the washer.

While the invention is particularly adapted for use in the field of conditioning for human comfort, it may be employed with equal success in conditioning of air for industrial purposes. The control of different banks of sprays and of resistances to flow of air through varying portions of the washer could be accomplished responsive to humidity and/or temperature conditions in the enclosure. The air would then be delivered at a temperature and relative humidity best suited

to the industrial requirements of the activity carried on in the enclosure.

Since certain changes in carrying out the above process and in the constructions set forth, which embody the invention may be made without departing from its scope, it is intended that all matter contained in the above description or shown in the accompanying drawings shall be interpreted as illustrative and not in a limiting sense.

I claim:

1. In an apparatus for conditioning air, means for establishing a stream of air flow, means for spraying a portion of said air stream with conditioning medium, other means for spraying a greater portion of the air stream with conditioning medium, and means for circulating conditioning medium through said first-mentioned spray means and then through said second spray means.

2. In an apparatus of the character described, means for establishing a stream of air flow, means for forming a plurality of banks of spray, different of said spray banks being arranged to contact with and condition different portions of said air stream, means for circulating conditioning medium through said spray banks in series, said spray banks being arranged so that different portions of the air stream pass through different numbers of spray banks, said spray banks and said circulating means being arranged so that those portions of the air stream passing through a greater number of spray banks are in heat exchange relation with the more effective conditioning medium and those portions of the air stream passing through a lesser number of spray banks are in heat exchange relation with less effective conditioning medium.

3. In an apparatus for conditioning air, means for establishing a stream of air flow, a plurality of spray headers, each of said headers being adapted to provide a bank of spray, means for supplying conditioning medium to each of said headers, each of said headers extending substantially in a straight line throughout its length and each of said headers being disposed at an acute angle to the direction of travel of said air stream, at least one of said headers being arranged to provide a bank of spray affecting all portions of said air stream, at least another of said spray headers being adapted to provide a bank of spray affecting a portion only of said air stream, and means for mixing different portions of said air stream subsequent to the passage of said air stream through said spray banks.

4. In an apparatus for conditioning air, means for establishing a stream of air flow, a plurality of spray header means, each of said header means being adapted to provide a bank of spray, means for supplying conditioning medium to each of said header means, at least some of the spray header means being disposed at an acute angle to the direction of travel of said air stream, at least one of said header means being arranged to provide a bank of spray affecting all portions of said air stream, at least another of said spray header means being adapted to provide a bank of spray affecting a portion only of said air stream, and means for mixing different portions of said air stream subsequent to the passage of said air stream through said spray banks.

5. In an apparatus for conditioning air, means for establishing a stream of air flow, a plurality of spray header means, each of said header means being adapted to provide a bank of spray, means for

- supplying conditioning medium to each of said header means, at least some of the spray header means being disposed at an acute angle to the direction of travel of said air stream, at least
- 5 one of said header means being arranged to provide a bank of spray affecting all portions of said air stream, at least another of said spray header means being adapted to provide a bank of spray affecting a portion only of said air
- 10 stream, means for mingling the different portions of said air stream subsequent to passage through said spray banks, and means for selectively controlling the supply of conditioning medium to different of said spray header means.
- 15 6. An apparatus according to claim 5 in which said means for selectively controlling the supply

of conditioning medium to said spray header means includes control means actuated in response to variations in air conditioning load requirements.

7. In an apparatus of the character described, 5 a casing, means for passing a stream of air through said casing, first spray-forming means for subjecting all portions of said air stream to intimate contact with sprayed conditioning medium, other spray-forming means for subjecting 10 a portion only of said air stream to intimate contact with sprayed conditioning medium, and means for supplying to said different spray-forming means conditioning medium at different temperatures.

WALTER L. FLEISHER.
